UNITED STATES PATENT OFFICE

LA VERNE R. JONES, OF ONEIDA, NEW YORK

DESIGN FOR A DIRECTION INDICATOR FOR AEROPLANE FIELDS

Application filed March 30, 1931. Serial No. 39,289. Term of patent 7 years.

To whom it may concern:

Be it known that I, LA VERNE R. JONES, a citizen of the United States of America, residing in Oneida, county of Madison, and State of New York, have invented a new, original, and ornamental Design for a Direction Indicator for Aeroplane Fields, of which the following is a specification, reference being had to the accompanying drawings, forming part thereof.

Figure 1 is a top plan view of my direction indicator for aeroplane fields.

Figure 2 is a side elevation.

Figure 3 is a front end view.

Figure 4 is a rear end view.

I claim:

The ornamental design for a direction indicator for aeroplane fields substantially as shown.

LA VERNE R. JONES
